UNITED STATES PATENT OFFICE.

EDWARD E. CLEMENT, OF WASHINGTON, DISTRICT OF COLUMBIA, ASSIGNOR, BY
MESNE ASSIGNMENTS, TO THE NORTH ELECTRIC MANUFACTURING COMPANY.

SYSTEM OF COMMUNICATION BY WIRE.

Application filed August 25, 1914. Serial No. 858,481.

My invention relates to the art of electrical transmission of intelligence over wires, and it has for its object the improvement of systems and apparatus for such transmission in divers particulars which will be hereinafter set forth.

This invention has to do particularly with systems in which localized initiating points are to be connected with other localized receiving points, for the purpose of permitting an individual at the first point who is calling, to communicate with an individual at the second point which he calls, and vice versa. Examples of such systems are found in the telephone equipments of cities and towns, and the customary method of effecting desired connections between pairs of points is through one or more centralized offices called exchanges, to which and between which extend lines or circuits from the several points to be served. The usual form of connection includes not less than three links, requiring not less than two circuit closing operations and usually many more. The first link is from the calling point to the nearest central office, the second link is a short connective link at the central office, becoming connected in response to the call with the incoming central office end of the first link, and thereafter as directed from the calling point, becoming connected at its other end to the central office end of the third link, which leads therefrom to the called or wanted point. A more complex connection would be built up of a first link from the initiating point to the nearest central office, a second link from that point to the end of a third link leading to a second central office, a fourth link leading to the end of a fifth link which in turn leads to the wanted or called point.

In building up connections of this sort, there have heretofore been employed two kinds of apparatus, viz manual and automatic. The manual kind comprises cords and plugs and jacks at each central office, the lines from the outlying points terminating usually on jacks, which are interconnected by means of the plugs and cords. The additional links required between central offices have been supplied in this case by providing other jacks and connecting lines. The automatic kind of apparatus comprises a sending device at each initiating point, and links at the central offices

connected to electrically driven or electrically controlled switching equipment, the movements of which may be directed and determined by said sending devices, acting through the first links from the initiating points to the central offices.

According to the present invention, certain features of these two kinds of apparatus are combined, and certain other features are omitted. I employ so-called automatic switches at the central offices, which acting in response to energy suitably applied and suitably directed, perform their functions selectively without direct manipulation. I omit sending devices at the initiating points, and instead thereof I employ controlling or sending devices at the central offices.

It will be convenient, in presenting this invention herein, to use the terminology and follow the layout and operation of a system of circuits and apparatus as they are used in the communication of intelligence telephonically. However it should be clearly understood that this invention of itself is not telephonic in its nature, that is to say it embodies switching means and circuits which might well be employed telegraphically or in signaling systems, as well as in telephone systems. The earliest developments of a centralized exchange system of interconnective apparatus and circuits supplying a plurality of originating points throughout a given area, occurred before the invention of the telephone. In that system the subscribers and central office operators were supplied with telegraph transmitters and receivers, and such signaling means might well be employed in the present case. It is of course self-evident that the only elements which are distinctively in a telephone exchange system are the telephone transmitting and receiving instruments themselves. Every circuit, every switching device, and all the appliances ordinarily employed in telephone systems, as well as the methods of signaling for connection and disconnection, "idle" and "busy", and the like, are essentially telegraphic and not telephonic in their nature. The present invention has nothing to do with telephonic instruments as such, nor with telephonic transmission over the circuit wires, nor with the tuning or other arrangements of the circuits to facilitate transmission; but on the contrary it has to do exclusively with the means

for signaling and establishing connected links, and in due course disestablishing the same; and as this arrangement happens to be particularly advantageous for use in a telephone system, the specific arrangements of apparatus and their specific operation as herein presented will facilitate such use, while they do not detract from its value in other directions.

- 10 The persons at the initiating and receiving points in a system of this character, who are to be connected in pairs for communication, will be herein designated "subscribers" as in a telephone system. The 75
15 persons who handle the traffic, that is to say direct the apparatus to make the desired connections at the central office or offices, will be herein designated "operators", as in a telephone system. A "calling subscriber" is one who desires a connection and a "called" or "wanted subscriber" is one with whom communication is desired.

The present invention briefly stated is practiced in the following manner:

- 25 I bring in the subscribers' lines to one or more central points and at each of these central points I place what I call a primary selector set, whereby the lines when calling are automatically connected to idle 80
30 trunks which lead out from primary selectors to the connective apparatus. For a small exchange this connective apparatus is located in immediate juxtaposition to the primary selectors. In a large exchange the 85
35 primary selectors are preferably located at convenient distributing points or branch exchanges, and the trunk lines run thence to the main office or "clearing house", where the connective apparatus is located.

- 40 There are two ways in which I can treat this connective apparatus. Using an exchange of 1000 lines for example, this would require, according to the usual calculation, 90
45 10% or 100 trunk lines, with a corresponding quantity of connective apparatus. According to the present invention I may either terminate these trunks in sets of connective switches, one set for each trunk for 95
50 selecting lines desired to complete a call, or I may apportion a smaller quantity of connective apparatus amongst the trunks and provide for a calling trunk to automatically select an idle set of connective apparatus. In other words, while there 100
55 may be 10% of trunks coming into the "clearing house", or leading from the primary selectors in a small exchange, there are cases where not more than 5% of actual connective apparatus is required. In 105
60 addition to the connective apparatus, a leading characteristic feature of the invention lies in the use of what I call secondary selectors for connecting the trunks when calling to idle operators for attention. The 110
65 operators ascertain the numbers wanted, and

then control the connective switches so as to produce the desired connection. This can be done in divers ways, of which I shall describe what I consider the simplest typical way herein. I shall also refer to other 70 ways, the underlying basis of all of them being that the line is automatically brought to and connected with the operator, and that the operator completes the connection by controlling further apparatus. The 75
80 duties of the operator are reduced to the performance of two acts only, viz obtaining the number wanted and setting the same up on buttons resembling those of an adding machine, thereby connecting a power operated transmitting machine to send the desired numbers and so operate the automatic switching apparatus.

The form of my invention which I have selected for illustration herein comprises trunks having access to the lines of the exchange at both ends of the trunk, and having access to the operators of the exchange at a point midway of the trunk. The operation of the trunk is as follows: When a line calls, the first end of an idle trunk automatically connects with the calling line; the trunk then automatically selects an idle operator's equipment and notifies the operator of the call; the operator then takes the subscriber's order and controls connecting apparatus at the second end of the trunk, whereby the second end of the trunk automatically connects with the desired line, thus connecting the calling with the called line; last of all my system provides for the automatic release of the operator's equipment from the trunk when the called line has been picked out, and provides for the automatic release of the trunk by the subscribers when the conversation has been completed.

Various details of apparatus will be described and claimed herein as well as the broad features above outlined. In addition to sets of selective relays for effecting connection between the calling lines and connective trunks and also between such lines and trunks when connected and the operators, I shall describe, illustrate, and claim specifically herein certain arrangements of traveling switches for performing these same functions. I shall also describe and claim operator's sending or controlling apparatus, the arrangement of which enables me if desired to use one common commutator or circuit breaker for the entire exchange. All the operators' sending wheels run synchronously with this commutator, and instead of having each wheel provided with a certain number of teeth to make and break the circuit, I provide each wheel with one unbroken tooth of sufficient length to take in the required number of impulses from the main commutator. Thus, the num- 115
120
125
130

ber 1 wheel has a very short tooth which corresponds to one tooth on the main commutator; the number 2 wheel has a tooth equal in length to two teeth on the commutator, and so on. Furthermore, there is no sparking at the contacts on the wheels, all makes and breaks being at the main commutator, for the reason that the make and break at each individual number wheel occurs a little before or a little after the corresponding make or break on the main commutator. Thus, for example, suppose the number "3" is to be transmitted, and the circuit of the number 3 wheel is therefore closed, the tooth on this wheel comes into contact with its spring pen during the interval of break on the main commutator, and remains in contact long enough for the main commutator to make and break three times, passing off of its individual spring during the third break of the main commutator. Thus it will be observed that all deterioration due to sparking and the kick of coils in the circuits is confined to the main commutator which I construct very solidly, preferably with compressed mica insulation and a carbon faced or solid carbon brush.

For the sake of convenience I shall illustrate and describe in this case selector and connector switches of the type known as the Strowger, such switches being well illustrated in the Letters Patent No. 815,176 and No. 815,321, issued March 13, 1906, to Automatic Electric Company as the assignee of Keith & Erickson. The primary selector and operators' trunk selecting switches may be of the same general type, at least in so far as regards their contacts and the way their contact arms and banks are arranged. In one particular there is a difference because my primary selector switches for answering calls do not have any vertical motion but simply rotate. Another point of difference is that I prefer to use a power drive with a clutch for each individual switch, although this is not material and a step by step movement, preferably driven from the main commutator and similar in every respect to the rotating movement of the patented switches referred to, may be employed.

In addition to the foregoing, I shall also illustrate and claim herein detailed forms of magnets and other apparatus useful in the systems herein presented.

This application is a continuation in part of my co-pending applications Serial No. 327,096, filed July 20, 1906 and Serial No. 328,096 filed June 23, 1906. Certain features of the apparatus claimed herein were originally disclosed in my prior application Serial No. 848,995, filed July 3, 1914, as a renewal of an earlier application filed November 13, 1907, Serial No. 402,027.

My invention is illustrated in the accompanying drawings in which:

Figure 1 shows the subscribers' stations and lines.

Figures 2, 3 and 4 shows portions of three primary selectors sets.

Figure 5 shows a set of signaling buttons and an impulse generator to work in connection with Figure 6.

Figure 6 shows a trunk circuit with a secondary set of relays which are normally disconnected from it.

Figure 7 shows automatic switch circuits.

Figure 8 is a modification of Figure 6 and works in conjunction with Figure 7.

Figure 9 shows apparatus equivalent to that of Figure 5 but adapted to operate in connection with Figure 8 and 7. In this figure the toothed number wheels are driven from a power shaft and the connection between the wheels and the shaft is made by a mechanically controlled clutch.

Figure 10 is a condensed diagram of a primary selector set.

Figure 11 and 12 are respectively a side and top plan view of a ten point relay used in my system.

Figure 13 is a plan view showing a strip of keys or buttons containing two signal lamps.

Figure 14 is a plan view showing the slide which controls or latches the various buttons.

Figure 15 is a sectional view of a portion of one of the strips of buttons.

Figure 16 is an end view showing the buttons mounted on an inclined support or cabinet.

Figure 17 is a side view showing a strip of ten buttons.

Figure 18 is a top plan view of Figure 16 showing the arrangement of the various sets of buttons, there being one of these outfits for each operator.

Figure 19 is a diagram showing switches instead of relays for primary and secondary selector sets.

Figure 20 is a skeleton diagram showing a number of subscribers' stations, a central office equipment having primary and secondary selectors only, each secondary selector being appropriated to one operator's key set, subscribers' lines being shown multiplied into both the primary selectors and the outgoing or selective automatic switches.

Figure 21 reproduces a portion of the trunk 30—31 of Figure 6 and shows also the corresponding portions of trunks 130—131 and 230—231, to illustrate the relation existing between the trunks, whereby one trunk always is held in readiness to respond to a call instituted by a telephone line.

Figure 22 reproduces the secondary selector equipment of Figure 6 in duplicate, showing the relation between the operators.

equipments and trunk circuits whereby an active trunk will select and connect with an idle operator's equipment.

Figure 23 shows a subscriber's station with its contacts terminating in a primary switch connected to a trunk circuit; and also a secondary outfit connected to a rotating or secondary switch which picks out a calling trunk.

Figure 24 shows a set of signaling buttons and an impulse generator to work in connection with Figure 23.

Figure 25 shows the circuits of an automatic switch.

Figure 26 is a modification of Figure 23 wherein the primary switch is connected directly to the line.

Figure 27 is still another modification showing the primary switch connected to the line and the secondary switch connected to the trunk.

Figure 28 is a schematic diagram illustrating the essential principles of the system shown in Figures 1 to 22 inclusive in which relay sets are employed for primary and secondary selection.

Figure 29 is a diagram of a modification similar to Fig. 21 but showing the transfer circuits between trunks extended by split contacts, and the trunk controlling magnets energized directly from the battery at each trunk.

Figure 30 is a diagram of a modification similar to Figure 20 but showing tertiary selectors intermediate the secondary selectors and the operator's sets.

Figure 31 is a diagram similar to Figure 28 showing the essential principles of the system of Figures 23 to 27 inclusive in which traveling switches are employed for primary and secondary selection.

Figure 32 is a schematic diagram showing three sets of selector and connector links, and three lines having multiple terminals in the banks of primary selector and connector switches, also showing in heavy lines one connection completed through the respective switches from a calling line to a called line.

Figure 33 is a diagram of a cord circuit in connection with which is illustrated the elemental use of a modified form of impulse sending system in which but one key set is used for a plurality of operators' trunks, the setting up of each set of numbers on the key set being registered on sets of locking relays individual to the trunks, which sets of locking relays may be individually associated with the single key set at the will of the operator.

Figure 34 is a diagram of the key set used in this modified system.

Figure 35 is a diagram of a gang switch used to cut the locking relays into and out of connection with the key set.

Figure 36 is a diagram of one set of num-

ber registering locking relays associated with an operator's trunk.

Figure 37 is a diagram of the impulse generator proper and multiple connections between sets of locking relays and the impulse generator.

Figure 38 is a diagram of the impulse control cams associated with the impulse generator.

Figure 39 outlines merely the extension conductors from the gang switch of Figure 35 to a second set of registering locking relays.

Figure 40 shows the second set of number registering locking relays.

Figure 41 illustrates the extension of connections between the impulse generator and the second set of number registering relays.

Figure 42 is a skeleton diagram illustrating the arrangement of Figures 33 to 41 inclusive.

Figures 1 to 19 inclusive of the drawings herein correspond precisely to Figures 1 to 19 inclusive of the drawings in Letters Patent No. 1,103,898, granted to me July 14, 1914, and Figures 20 to 22 herein correspond precisely to Figures 21 to 23 in said Letters Patent. Reference is therefore made to said Letters Patent for a full description of said figures, and detailed description herein will be confined to the apparatus and circuits illustrated in Figures 23 to 30 inclusive.

Referring to Figures 23 to 27 inclusive and particularly to Figure 23, the subscriber's station A comprises apparatus usual in common battery systems consisting of the transmitter, receiver, ringers, condenser and switch-hook. The line wires from this station terminate in the line relay M through the normally closed contacts of the cut-off relay M'. The relay M when energized places battery on the contact z^{60} in the bank of the switch Z. This switch when idle is constantly rotating, being normally connected to a constantly rotating shaft by means of a friction clutch z^{16} engaging the clutch z^{18} which is rigidly fastened to the shaft. This clutch is controlled by the magnet D²⁰ which when energized attracts the arm d^{20} , disengaging the clutch z^{16} thus causing the spindle Z²⁰ carrying the wipers to come to rest. This magnet D²⁰ is energized when the test wiper z^{30} rests on the test contact z^{60} and the line 1—2 is calling and holding relay M energized. The trunk wipers z^{40} and z^{50} are disconnected from the trunk wires 30 and 31 respectively by the normally open contacts of the relay D¹⁰. This relay is energized in multiple with the magnet D²⁰ and is held energized by the action of the relay D when the trunk is connected to the calling line. The relay D is connected to the grounded side of battery and is tapped to the tip side of the trunk 30 while the relay D' connected to the free side of battery

is tapped to the sleeve side of the trunk 31, thus furnishing battery current to the calling subscriber. The relay E is the starting relay and is operated when the talking trunk 5 is connected to a secondary trunk shown in the lower portion of the drawing. This relay when energized locks itself through the contacts e^3 and e^4 and is thereafter controlled by the relay D' through the contacts d^5 and 10 d^6 . The relays S and S' respectively, each have one terminal connected to the contacts z^{46} and z^{56} in the secondary switch Z'. The relay S' has its other terminal connected to the free side of battery. The relay S which 15 responds to impulses from the sending machine shown in Figure 24, repeats these impulses over the tip side of the trunk 30* to the switching mechanism in Figure 25. The relays S and S' also furnish battery current 20 for the operator's set in the secondary outfit and at the same time connect her talking set to the trunk wires enabling her to converse with the calling subscriber.

The secondary switch Z' is identical with 25 that of Z and its magnet D³⁰ is energized by the action of the relay D' in the same manner that the magnet D²⁰ is energized by the action of the relay M. The relay D⁴⁰ is connected in multiple with the magnet D³⁰. 30 The relay T in the secondary outfit is provided with a make before break contact and through this contact is connected to the wiper z^{55} , when the relay D⁴⁰ is operated. When the switch Z' comes to rest with its 35 wipers in connection with contacts leading to the talking trunk, the relays T and S are connected in series. The relay T becoming energized locks itself through the contacts t and t^2 opening the contact t' thus 40 disconnecting itself from the wiper z^{56} and taking battery off relay S. The action of the relay S closes the contacts s and s' thereby completing the circuit of the relay E which remains locked through the contacts e^3 and e^4 and under control of the 45 relay D'. Ground is placed on the test contact z^{36} over the wire 18 when the relay D' is energized upon being connected to the line and is removed by operation of relay E. The operation of the relay T closes the circuit of the lamp L which is the signal to the operator that there is a call. The relay H has its circuit closed 50 when the operator depresses the starting button K^x in Figure 24. This relay in turn closes the circuit of the relay H' which in turn closes the circuit of the motor in Figure 24. After the operator releases the button K^x the circuit of the relay H is 55 maintained through the pen q^6 which rests on the metal portion of the wheel Q²⁵, the metal portion being connected to battery. The circuit of the relay T is normally completed through the contacts h^{10} and h^9 of 60 the relay H', but after this relay is ener-

gized the circuit is maintained through the contacts h^2 and h^3 of the relay H.

Referring now to Figure 24 a very important feature of this invention is shown 70 wherein a common impulse generator supplies the entire exchange. Individual selector wheels having teeth of different lengths are provided. These teeth are so proportioned and the wheels so run relatively to the main circuit at the commutator that they will always make and break a little before and a little after the commutator is made and broken respectively, which positively avoids sparking at the contact pens. This arrangement is shown diagrammatically in Figure 24 wherein I have 80 illustrated the main commutator, one set of number wheels, an electric motor for driving the shaft common to all of these, and a set of operators' buttons similar to those used in selective ringing systems in a great many exchanges. Any type of button can be used provided that when one button is depressed it must be kept locked or in an 85 indicating position until some other button is depressed whereupon the first button must be released and assume its normal position. In the accompanying drawing I have shown these individual wheels being driven by a motor which starts up when the operator depresses the starting button. In place of the motor I may have the same 90 operated by a magnetically controlled friction clutch which when operated by the operator pressing the starting button connects them to a constantly rotating shaft. The wheels, Q', Q², Q³, Q⁴, and Q⁵ are provided with teeth of different lengths, the tooth on wheel Q' being the shortest while 95 that of Q⁵ is the longest. The tooth of the wheel of Q' in passing over a contact pen transmits one impulse through the medium of the common commutator Q¹⁰. The tooth of the wheel Q⁵ in passing over one of these pens transmits five impulses 100 through the same medium. A complete machine will have ten of these wheels so that any digit from one to ten can be indicated by sending the appropriate number of impulses. In the drawing in order to economize 105 space and avoid confusion, I show only the first five wheels. In practice these wheels are all one, the teeth being formed upon the surface of a drum which can be driven by a suitable motor or shaft. The speed which I have found most suitable for 110 this device and for the type of switches I here illustrate is approximately twelve revolutions per minute. For a 100 line exchange 115 which I am illustrating the first four wheels will be provided with three pens and the remaining six provided with two pens each. These pens through which the impulses are transmitted are connected in their proper 120 order to the buttons K', K² and K³. The 125 130

pen q' is connected to the individual spring 71 of the key k' in the set K' by means of the wire 74. Similarly the pen q' of the wheel Q^2 is connected to the spring 71 of the 5 key k^2 of the set K' by the wire 75, and so on. The succeeding wires of all the pens go to the individual springs of the keys of the set K' . The second set of springs q^2 are connected in the same order to the individual 10 springs of the keys belonging to the set K^2 ; the third set of springs q^3 are similarly connected to the individual springs of the key set K^3 . The layout in this figure is intended for an exchange of one hundred lines 15 or less the two sets of keys K' and K^2 serving to control two sets of number wheels for selective purposes while the third set of keys K^3 is intended in the present case for selective ringing on party lines.

20 The wheel Q containing the three teeth transmits what is commonly called the rotary impulses to affect the side switch mechanism in the connector switch. The impulses from this wheel instead of being controlled by battery through the medium of 25 the commutator Q^{10} send grounded impulses operated directly by the teeth coming in contact with a single pen. The wheel Q^{25} has an insulated point upon which the contact spring q^6 normally rests. If this wheel is started by the operation of the motor the pen q^6 riding on the metal portion of the wheel closes the circuit of the motor which 30 will continue to run until the wheel Q^{25} has made one complete revolution and the pen q^6 again rests on the insulated portion. The teeth on the wheel Q^{25} are so set that they come successively in contact with the pen q^6 immediately after the teeth of the 35 impulse wheels have ceased sending their respective impulses.

The common springs 78 of the key set are connected together to a common wire 79. This common wire carries to the switches in 40 proper sequence the actuating impulses.

To illustrate clearly the operation of this device, suppose it be desired to transmit over the wire 79 the number 43-3. The operator depresses the fourth key in the first set and 45 the third key in the second set, and finally the third key in the third set. Thus the spring q' of the wheel Q^4 becomes connected to the wire 79; the spring q^2 of the wheel Q^3 becomes connected through its wire to the 50 wire 79. Now as the drum or the wheels rotate what happens is this: First, four impulses from the wheel Q^4 , then a single impulse from the wheel Q , then three impulses from the wheel Q^3 ; then one impulse from 55 the wheel Q ; then three impulses from the wheel Q^2 , and finally a single impulse from the wheel Q , so completing the signal. Any 60 one familiar with the Strowger system of switches will at once perceive that the wires 65 79 and 82 can be connected directly to the

vertical and the rotary sides of a switch trunk, respectively, and the impulses will then serve to operate the switches perfectly. I may here state that the sole function of the wheel Q^{25} with its wiper q^6 is simply 70 to send in one complete set of impulses and then stop. Obviously, if the operator sets up the signal keys and the impulses were permitted to go directly into the switch circuits without any starting point, great confusion would result. For this reason I have the various signal wheels always come to rest at a normal starting point which is controlled directly by the wheel Q^{25} and the pen q^6 . 75

The circuits of Figure 24 thus described are particularly adapted to operate with the trunk circuit shown in Figure 25.

Referring now to Figure 25 the connector switch consists of the vertical relay V which 80 responding to impulses over the vertical side of the trunk operates the vertical magnet V^2 which in turn causes the spindle Z carrying the wipers z' and z to step up vertically. The relay V connected to the rotary side of the trunk responds to rotary impulses and operates the private relay U which in turn causes the mechanically operated side switches to move one point, disconnecting the 85 vertical magnet V^2 and in its place connecting the rotary magnet V^3 , and at the same time through the side switch w^{50} connects the tip side of the trunk to a contact in the private relay which, when closed, connects the test relay J' . The relay V responding to a second set of impulses over the vertical side of the trunk operates the rotary magnet V^3 causing the spindle Z to rotate and bring the wipers to rest on contacts leading 90 to the desired line. The next rotary impulse coming in operates the private relay U in the same manner as before, causing the side switches to make still another movement. This last movement of the side switches disconnects the rotary magnet and in its place 95 connects the relay R' which, when operated, closes the circuit of the locking relay X' which completes the circuit of the ringing relay Y . The relay R' is now in position to be controlled by the third set of impulses coming in over the vertical side of the trunk. This relay controls a set of relays W and these relays in turn control generator current of different frequencies or polarities. All of these relays are self-locking and have 100 a common wire controlling their locking circuits. This common wire 150 leads to a normally open contact in the relay X' . This relay becoming energized at the first impulse of the third set places battery on this wire. The relay R' is also energized at this junction and after the first impulse its armature drops back and closes the circuit of the relay W^4 through the normally closed contacts of the relay W^5 . The next impulse operating 105

130

the relay R' closes the circuit of the relay W^5 through the contacts of the relay W^4 and the normally closed contacts of the relay W^6 , and after the second impulse the circuit contacts of the relay W^6 are closed through the contacts of the relay W^5 . At the third impulse the circuit of the relay W^7 is closed through the contacts of the relays W^4 and W^6 and the normally closed contacts of the relay W^8 ; at the end of the third impulse the circuit of the relay W^8 is closed through the contacts of the relays W^5 and W^7 and the normally closed contacts of the relay W^9 . At the fourth impulse the circuit of the relay W^9 is closed through the contacts of the relays W^4 , W^6 and W^8 . It will be seen from the foregoing description that I have a set of step by step relays controlled by the relay R' , the first relay of the set becoming energized when the relay R' becomes deenergized, the second relay becomes energized when the relay R' becomes energized the second time, and the third relay becoming energized when the relay R' again becomes energized, and so on. This system of relays can be carried on indefinitely. The relay W^5 becoming energized disconnects generator G' and in place connects the generator G^2 to a contact in the ringing relay Y , and the relay W^7 becoming energized disconnects the generator G^2 and in its place connects the generator G^3 and the relay W^9 becoming energized disconnects the generator G^3 , and in its place connects generator G^4 .

Battery is supplied to the called subscriber through the relay R and retardation coil I which are normally connected to the calling end of the trunk. The locking circuit of the relay X' is controlled jointly by the normally closed contacts of the relay R and the normally open contacts z^3 and z^2 controlled by the spindle Z . If the called subscriber answers, the relay R becomes energized, disconnecting the relay X' which in turn cuts off the ringing relay Y . If the called subscriber does not answer the relay X' is disconnected when the calling subscriber hangs up his telephone disconnecting the switch Z which upon returning to its normal position opens the contact springs z^2 and z^3 . The calling subscriber at the end of the conversation automatically places battery on both sides of the trunk circuit operating the relays V and V' simultaneously, the action of which closes the circuit of the test relay J' which in turn closes the circuit of the release magnet J . Battery is placed on both sides of the trunk circuit by the combination of relays in the talking circuit as follows: During conversation the relays D , D' and E remain energized. When the subscriber hangs up his receiver the relay D is the first to fall back or become deenergized which places battery through its normally closed contacts to the contacts in the relay E and from there to the trunk circuit. The next relay to drop back or to become deenergized is the relay D' which is kept energized longer than the relay D on account of being in series with the line cut-off relay through the primary selector sets. After the relay D' becomes deenergized the relay M is disconnected and thus battery is removed from both sides of the trunk.

Referring now to Figure 26 instead of providing each trunk with a primary switch I connect one of these switches to each line and instead of being constantly rotated, it is normally at a standstill and only starts to rotate when the subscriber closes the line circuit by removing his receiver. These switches contain contacts leading to talking trunks. When the line relay M is energized, the magnet D^{20} has its circuit completed and drawing down the arm d^{20} the clutch z^{16} engages the constantly rotating clutch, thereby causing the spindle z^{20} carrying the wipers to rotate until an idle trunk is reached. When a trunk is idle its multiple wire leading to the contact z^{60} is connected directly to battery through the normally closed contacts of the relay D . This relay when idle is, of course, deenergized and when busy is energized and battery is disconnected from the test contact z^{60} . When this trunk is busy, the difference of potential at contact z^{60} is such that a test wiper z^{30} from any other switch in passing over one of them will not cause its cut-off relay M' to be operated. To make this clear I will describe the method of operation which is as follows: The subscriber, removing his receiver, closes the circuit of the relay M which, attracting its armature, closes the circuit of the magnet D^{20} causing the switch to rotate. When the wiper z^{30} makes connection with a contact leading to an idle trunk, such as is shown in the accompanying drawing, the relay M' immediately gets direct current from battery B through the contacts d^4 and d^5 . The energizing of the relay M' by this path disconnects the relay M and connects the line wires 1 and 2 to the extensions 3 and 4 respectively, and as soon as this happens, the relays D and D' become energized through the subscriber's station. The relay D is provided with a set of make before break contacts and upon operating disconnects direct battery from the relay M' by here breaking the contacts d^4 and d^5 , but at the same time it closes the contacts d^6 and d^7 . The resistance coil I' is connected to battery and to the contact d^6 , and the relay M' is thereafter held energized by current flowing through this coil. It of course follows that the test wiper of any other switch in passing over this contact z^{60} will not operate its associate cut-off relay. The

balance of the circuit and the operation of the same is identical to that shown in Figure 1 and need not be described.

Referring now to Figure 27, I have shown a switch connected to each line as in Figure 26, but instead of having the secondary switch connected to a secondary outfit, I have it connected to the talking trunk. In this case when ground is connected to the starting wire 18 by the relay D' the circuit of the magnet D³⁰ is closed, and upon operating draws down the arm d³⁰ causing the switch to rotate. When the wiper z³⁵ finds an idle secondary outfit which would have battery connected to the contact z⁵⁶ through the relay T, the relays S and T will be connected in series and the relay S operating the relay E in the same manner as in Figure 23 disconnects ground from the starting wire 18 thereby opening the circuit of the magnet D³⁰ causing the switch to come to rest. The balance of the circuit and operation is identical with that of Figure 23 and need not be described here.

These two Figures 26 and 27 are simply modifications of Figure 23, Figure 23 being the preferred form. These various modifications are shown so as to fully cover the different methods of connecting a calling line to a talking trunk and thereafter connecting the talking trunk to a secondary outfit for the purpose of completing the connection through switching mechanism on the calling end of the talking trunk.

I will now describe the complete operation tracing a connection from the calling to the called subscriber, assuming that subscriber A in Figure 23 is the calling subscriber. When he takes down his receiver, line circuit 1 and 2 is closed and the relay M is energized. The energizing of this relay places battery on the contact z⁶⁰ through the closing of the contacts m and m'. When the test wiper z³⁰ of the normally revolving switch Z reaches this contact, the circuit of the magnet D²⁰ is closed through the contacts d³ and d⁴ of the relay D and at the same time the circuit of the relay D¹⁰ is closed in multiple with this magnet. The energizing of the magnet D²⁰ draws down the arm d²⁰ separating the two clutches z¹⁵ and z¹⁶ causing the spindle Z²⁰ carrying the wipers z³⁰, z⁴⁰ and z⁵⁰ to come to rest. The energizing of the relay D¹⁰ closes the contacts d¹¹ and d¹² and d⁹ and d¹⁰ thereby connecting the trunk onto the line extensions 3 and 4. The relays D' and M' are thus placed in series and the energizing of the relay M' disconnects the relay M and removes battery from the test contact z⁶⁰. As soon as the relay M' is operated, the relay D becomes energized through the subscriber's station and attracting its armature maintains the circuit of the magnet D²⁰ and relay D¹⁰ through the contacts d² and d³. The energizing of the relay D' places ground on the starting wire 18 through the normally closed contacts e and e' of the relay E. The wiper z³⁵ of the normally revolving switch Z' on reaching this contact closes the circuit of the magnet D³⁰. The energizing of this magnet draws down the arm of d³⁰ causing the spindle carrying the wipers to come to rest on contacts leading to the calling trunk. The first thing that happens is that the relay T is connected in series with the relay S by the following path: battery B, 29, 42, h⁹, h¹⁰, 41, T, t², t', 40, armature and contact of relay D¹⁰, z⁵⁵, z⁵⁶, 32, S to ground. The relay T becoming energized locks itself through the contacts t and t² and opening the contacts t' and t² removing itself from the wire 40 so as not to interfere with impulses that are to be transmitted over this wire. The relay S being momentarily energized, attracts its armature and closes the circuit of the relay E by the following path: battery B, 28, 21, s, s', 20, E, 15, d⁵ to ground. The relay E thereupon locks itself through the contacts e⁴ and e³ as the contact e⁴ is connected to the winding while the contact e³ is connected to battery. The operation of this relay disconnects the starting wire 18. The energizing of the relay T closes the circuit of the lamp L causing it to glow. The operator perceiving the signal, depresses the listening button k^x connecting her talking set on wires 49-50 across the wires 32 and 33 through wires 40-39 and wipers z⁵⁶ and z⁴⁵. The talking set being bridged across the wires 32 and 33, closes the circuit of the relays S and S' thus connecting the talking set to the trunk wires through the contacts s², s³, s⁷ and s⁸ respectively. These two relays supply the operator's set with battery current and at the same time connect the set across the trunk wires enabling her to converse with the calling subscriber. The action of these relays at this time places battery on both trunk wires 30^x and 31^x through the contacts s⁴ and s⁵ and s⁹ and s¹⁰ respectively. Battery current going over both sides of the trunk at the same time restores the switching mechanism in case it has been left in an unrestored position when the trunk was last used. The operator now being connected to the calling subscriber and asking for the number depresses the buttons of her key set corresponding to the number desired. For illustration, suppose the number asked for was 43-3, the first two digits representing the telephone number and the last digit representing the signaling number as I wish to illustrate the manner of selective party-line ringing. The operator depresses the fourth key in the set K², the third key in the set K², and the third key in the set K³. Having thus set up the number the operator restores her listening key

K⁴ and closes the starting key K^x thereupon closing the circuit of the relay H, Figure 23, by the following path: battery B, 21⁰, 82, H to ground. The energizing of this 5 relay closes the circuit of the relay H' by the following path: battery B, 29, h, h', H' to ground. The energizing of the relay H' opens the locking circuit of the relay T but the circuit is maintained through the contacts h² and h³ of the relay H. The action 10 of the relay H' closes the circuit of the motor Figure 24 through the contacts h⁶ and h⁷ the arrow points indicating a source of power. Referring now to Figure 24 the starting of 15 the motor X causes the impulse wheels to rotate. At the first movement of the wheels, the pen q⁶ rides on the metal portion of the wheel Q²⁵, thus maintaining the circuit of the motor X, after the starting button is 20 released. The common wire 79 receives the vertical impulses, that is to say, impulses from the wheels Q', Q², Q³, Q⁴, etc., and from this wire the impulses are conveyed to the relay S through the path 79, 83, 40, contacts of D⁴⁰, z⁵⁵, z⁵⁶, 32, S, earth. The rotary 25 impulses, or the impulses from the wheel Q are conveyed to the relay S' through the path Q, q, 84, 39, z⁴⁵, z⁴⁶, 33, S', 28, B. The first set of impulses to be received by the 30 relay S are those transmitted from the pen q' of the wheel Q⁴. These impulses pass through the contacts of the fourth button of the set K'.

The next impulse is a rotary impulse sent 35 to the relay S' by the wheel Q. The second set of vertical impulses are sent to the relay S by the pen q² of the wheel Q⁸ through the contacts of the third button of the set K², then follows another rotary impulse from 40 the wheel Q. The third set of impulses are sent from the pen q³ of the wheel Q³ through the contact of the third button of the set K³, then follows the third rotary impulse. After the last set of impulses, or after one complete revolution, the pen q⁶ of the wheel Q²⁵ 45 rests on the insulated portion and the relay H becomes deenergized. The deenergizing of this relay opens the locking circuits of the relay T, thereby disconnecting the secondary set from the talking trunk. The deenergizing of the relay H releases the relay H' and extinguishes the lamp L. It, of course follows, that as the operator's talking 50 set is connected to the secondary set and the secondary set is disconnected from the talking trunk the operator is prevented listening in on the trunk during conversation. The secondary set is only connected to the talking trunk while the number is being taken, and while the impulses are being sent.

Referring now to Figure 25 I will show how these impulses from the secondary set which operate the relays S and S' in Figure 23 control the switching mechanism in this 55 figure. I have already shown how the call-

ing subscriber is automatically connected to a secondary set through a talking trunk, the secondary set simply containing the operator's set and impulse transmitter. I have also shown how these impulses from the various wheels affect the relays S and S'. The first set of impulses which, in this case number four, causes the relay S to attract its armature four times and send that number of impulses over the wire 30^x through the contacts s⁴ and s⁵. These impulses coming in over what is known as the vertical side of the trunk operate the vertical relay V which in turn closes the circuit of the vertical magnet V² by the following path: ground v³, v², u, u', 306, switch arm w⁵⁰, 321, V², 309, to battery B. The operation of this magnet causes the spindle Z carrying the wipers z and z' to step up vertically opposite a row of contacts corresponding to the number of impulses sent from the secondary set. After this first set of impulses a rotary impulse is placed on the wire 31^x or the rotary side of the trunk by the action of the relay S'. This impulse operates the relay V', which 70 in turn closes the circuit of the private relay U which causes the side switch to move one step, placing the various arms, w⁵⁰, w⁶⁰, w⁷⁰, and w⁸⁰ on the second contacts. The movement of the arm w⁵⁰ disconnects the vertical magnet V² and in its place connects the rotary magnet V³, while the operation of the arm w⁸⁰ connects or places the test relay J' 75 in position to test the tip side of the line. The second set of impulses numbering three, 80 operates the relay V which in turn closes the circuit of the rotary magnet V³ causing the spindle Z to rotate and bring the wipers to rest on contacts leading to the desired line. The second rotary impulse now coming in 85 operates the relay V' which closes the circuit of the private relay U causing the side switch to take another step bringing the switch arms to rest on the third contacts. During this second rotary impulse while the 90 relay U is energized the test relay J' is connected directly to the tip side of the line and if the line were busy the relay J' would become energized and closing the circuit of the release magnet J restore the switch to its 95 normal position. We will take it for granted that the called line is idle, so therefore the switch arms rest on their respective contacts. The switch arm w⁵⁰ disconnects the 100 rotary magnet V³ and in its place connects the relay R'. The switch arms w⁶⁰ and w⁷⁰ close their respective trunk circuits while the switch arm w⁸⁰ disconnects the test relay from the tip side of the line or trunk. The 105 calling subscriber is now connected to line number 43. The third set of impulses now coming in operate the relay V which in turn closes the circuit of the relay R'. The first 110 one of these impulses affecting this relay causes it to close the circuit of the relay X', 115 120 125 130

by the following path: ground, p^2 , p^3 , X' , 320, p' , p , 309, to battery B. This relay now locks itself through the contact x , the contact x being connected to ground through 5 the springs z^2 and z^3 which are controlled by the switch spindle. The winding of the relay X' is connected to battery through the normally closed contacts p , p' of the relay R. Battery is now placed on the locking 10 contacts of the ringing relay set W through the common wire 150 and the contacts x^2 and x^3 of the relay X' . The number of impulses in this last set are three which correspond to the ringing number of the desired 15 party. The first impulse affecting the relay R' does not affect any of the relays in the ringing set W, but immediately after the first impulse when the relay R' drops back the circuit of the relay W^4 is closed by the 20 following path: battery B, 309, x^3 , x^2 , p^6 , p^7 , 315, w' , w^2 , w^4 , to ground. The second impulse coming in operating the relay R' closes the circuit of the relay W^5 by the following 25 path: battery B, 309, x^3 , x^2 , p^6 , p^5 , 314, w^6 , w^5 , w^{13} , w^{14} , W^5 to ground. The operation 30 of the relay W^5 disconnects the first generator G' and connects the generator G² in its place to the normally open contact in the ringing relay Y. Immediately after 35 the second impulse the relay R' dropping back closes the circuit of the relay W^6 through the path already described to wire 315 and from there through w' , w , w^8 , w^9 , W^6 , to ground. The third impulse coming 40 in closes the circuit of the relay W^7 through the path already described to wire 314 and from there through w^6 , w^5 , w^{13} , w^{12} , w^{21} , w^{22} , W^7 to ground. The operation of the relay W^7 disconnects generator G² and in its 45 place connects the generator G³ which is of proper frequency or polarity to ring the bell at the desired station. Immediately after the third impulse the circuit of the relay W^8 is closed in a manner similar to that already 50 described in connection with the other relays.

The proper generator current is now placed on the contacts in the ringing relay Y. One terminal of the relay Y is connected directly to an interrupting machine Y' and the interrupting machine itself is connected directly to battery. The other terminal of the relay is connected to ground 55 through the normally closed contacts p^{10} and p^2 of the relay R' in series with the contacts x^4 and x^5 of the relay X'. While the ringing impulses are being sent and the proper relay in the ringing set W is being selected the relay Y is not affected on account of the rapid making and breaking of the contacts p^{10} and p^2 . After the impulses have been sent and the relay R' is in its normal position the circuit of the relay Y is closed and opened through the interrupting machine Y'. When its circuit is closed 60

the relay Y opens the trunk and places generator current on the calling end of the trunk. This current is placed on the line intermittently and during one of these intermissions when the relay Y is de-energized and the called subscriber removes his telephone the relay R becomes energized and opening the contacts p and p' releases the relay X' which in turn opens the circuit of the ringing relay Y, thus preventing any further generator current being placed on the line. The retardation, or resistance coil I' is provided to hold up the cut-off relay of the line while generator current is being sent over the line. 70 75 80

From the foregoing description it will be seen that the two subscribers are provided with a clear talking circuit, battery being supplied to the called subscriber from the connector switch and battery supplied to the calling subscriber from the trunk. In this present arrangement there are two sets of condensers in this talking circuit and also an additional bridge caused by the relays V and V' which are not needed at this juncture. The relay X' which is released when the called subscriber answers also unlocks the relays in the ringing set W thus preventing a waste of current. 90 95

At the end of the conversation the calling subscriber hanging up his telephone deenergizes the relay D and this relay dropping back releases the relay D¹⁰ which upon falling back opens the trunk circuit disconnecting the relay D' and the line cut-off relay M'. The relay D being the first to fall back places battery on both sides of the trunk leading to the switching mechanism through the contacts e^5 , e^6 , and e^7 , e^8 . The relay D' is the next relay to drop back thereby releasing the relay E, removing the battery from both sides of the trunk. From this combination it will be seen that a momentary impulse has been placed simultaneously on both trunk wires. Referring now to Figure 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790

Detail description of Figures 28 and 31 is not supposed to be necessary. In Figure 28 the primary and secondary selectors are indicated at PS and SS respectively, the operators' sets at OS, the first selector trunks at ST, the operators' trunks at OT, the first selector at X, the second selectors at Y, and the connectors at Z; and finally the sending machine at SM. Subscribers' stations are marked Sub, and the other elements are numbered 1, 2 and 3 to indicate their order or use. In Figure 31 in similar fashion, subscribers' stations are indicated at 1, 2, 3, 130

and 4, their line multiples are designated m , the primary traveling switches at PS, and the selective switches, the trunks and operator's equipment as in Figure 28. The 5 secondary switches are designated as SS and all the other elements the same as in Figure 28. In Figure 32 the same general designations are followed as in the preceding figures, and in addition the test relays are 10 marked T^z.

In Figure 29 I show a modified means of transferring the service from one primary trunk to another, or in other words successively placing the primary trunks in readiness 15 to receive calls. This means differs from the means disclosed in Figure 21 in that the contacts of the relays D⁰, 1D⁰, etc. which control the trunk controlling magnets D^x, 1D^x, etc., and the transfer circuits between 20 trunks are split in such a manner that the transfer circuits between trunks and the trunk controlling magnets D, 1D, etc. are directly connected to battery at their respective trunks instead of by way of a series 25 circuit extending through a plurality of contracts from trunk to trunk.

The system of distribution to operators may be extended and enlarged by including 30 double and triple selection between the primary trunks and the operators' sets. Such an arrangement is disclosed in Figure 30 in which a tertiary selection of operators' trunks by tertiary switches intermediate the secondary selector switches and the operators' sets is clearly outlined. The tertiary 35 selectors are constructed and operated similarly to the secondary selectors. For extremely large exchanges such additional distribution to operators may be found very 40 desirable under certain load conditions.

So also the impulse sending system controlled by the operators may be varied in form, and I show in Figures 33 to 41 inclusive (which are to be arranged according 45 to the diagram of Figure 42) one of my improved forms of this system. The cord circuit of Figure 33 is illustrative merely, for the impulse sending system I herein-after describe may be associated by means 50 of secondary selectors with any of the primary trunks disclosed in the foregoing systems or other systems of the same general character. There is used but one key set per operator, thus cutting down the apparatus 55 at the operators' desks. Each operator's trunk however, is provided with a set of number registering relays, while under the control of the operator is a gang switch by means of which any set of number 60 registering relays may be temporarily associated with the key set, whereupon the number may be registered upon the relays by operating the key set in the usual manner and the key set thereafter dissociated 65 from one set of relays to be immediately

associated with another set of relays. Thus it will be apparent that with one impulse generating apparatus and one key set an operator can keep continuously busy setting up the numbers of calls desired without 70 waiting for the impulse generating outfit to complete a cycle of operations.

In Figure 34 is shown the single key set KS, and a plurality of sets of on and off relays O', F', O², F², etc. of the type disclosed in my application Serial No. 309,010. These on and off relays are operated from the sending machine IG of Figure 37. The individual contacts of the various rows of keys of the key set KS are extended to the 75 central contacts of the double-throw sets of contacts of the gang switch GS. The outside contacts of each set of this gang switch GS are connected with the individual relays of the relay sets RE' and RE² respectively. 80 There is provided in each set one relay for each key of the key set KS and the arrangement is such (as clearly indicated) that the relay when energized through pressure of the corresponding key of the set KS will 85 lock up over a circuit under control of the sending machine IG. Thus according to the position of the gang switch GS relays of one set RE' or the other RE² may be individually energized and locked up in accordance with the number set up on the key 90 set KS. Each relay is arranged to connect with the associated operator's trunk that one of the impulse controlling cams IC of Figure 38 corresponding to its number. 95 Thus, when a starting key SK is pressed, that associated group of relays energized at the beginning of any cycle of the impulse generator IG operates during that cycle to control the transmission to the associated 100 operator's trunk of the number registered. At the end of such transmission the set of relays is unlocked at the same time the off-relay F' is deenergized and is thereafter ready to receive the registration of another 105 number. In the meantime during the cycle of operation just considered, relays of the second set RE² will have been operated to register a second call, the gang switch GS having been simply thrown from one position to another without waiting for the transmission of the number set up on the first set. The relays of this set RE² lock 110 up in conjunction with the off-relay F², and starting key SK² having been pressed, the moment the preceding cycle of operation of the impulse generator IG is completed, the transmission of the number registered on the second set of relays takes place.

I do not claim herein the decimal sets of relays illustrated in Figures 2 to 22 inclusive as primary selector sets and secondary selector sets, nor a system of this kind employing such relays in such a manner, 125 These matters are claimed broadly and spe- 130

cifically in my prior copending application Serial No. 323,096, filed June 23, 1906, together with other features. Similarly I do not claim herein the specific combination 5 of traveling switches shown in Figure 23 since that is claimed in my prior copending application Serial No. 327,096, filed July 20, 1906.

It will be noted that in Figure 33 that I 10 have provided the cord circuit with an automatically operated operator's listening key, by means of which the multiplied operator's set is cut in when the call is answered and cut out when connection is made with a 15 calling jack. Further it will be noted that each operator's trunk (33 and 34) is provided with two trunk keys TK' , TK^2 , by means of which each operator's trunk may be associated at will with any one of the 20 plurality of connective links. These trunk keys may be supplanted by secondary selector switches and associated apparatus as previously indicated and described herein and in connection with other systems of my 25 invention.

What I claim is:

1. In a connective system, the combination of subscribers' lines; trunks; automatic selective switches associated with said 30 lines and trunks and adapted to connect a calling line and an idle trunk, thereby making the connected trunk a calling trunk by virtue of its connection with a calling line; and other automatic selective switches associated with said trunks and adapted to connect a calling trunk to an operator's position, substantially as described.
2. In a connective system, the combination of subscribers' lines; trunks; means 40 for interconnecting calling lines and trunks; operators' trunk-control equipments; automatic means for connecting a calling trunk with an operator's trunk-control equipment; an operator's telephone; and means where- 45 by the operator may connect her telephone with the circuits of her trunk-control equipments, substantially as described.
3. In a connective system, the combination of subscribers' lines; trunks; Y- 50 switches adapted to connect said lines and trunks; operators' trunk-controlling equipments; other Y-switches associated with said trunks and adapted to connect said trunks and said operators' trunk-controlling 55 equipments and becoming operative by reason of the connection of a trunk with a line; an operator's telephone; and means for connecting said telephone to said operator's controlling set and thus through said 60 Y-switches to the trunk and to the line, substantially as described.
4. In a connective system, the combination of subscribers' lines; trunks; Y-switches 65 adapted to connect said lines and trunks; operators' trunk-controlling equipments;

other Y-switches associated with said trunks and adapted to connect said trunks and said operators' trunk-controlling equipments and becoming operative by reason of the connection of a trunk with a line; an operator's telephone; means for connecting said telephone to said operator's controlling set and thus through said Y-switches to the trunk and to the line; and means for automatically disconnecting the operator's control equipment from a trunk after the desired connection has been set up, substantially as described. 70

5. In a connective system, lines; trunks; means for connecting a trunk with a calling line; secondary means for connecting a trunk with an operator's set; a relay associated with the trunk for rendering said secondary means operative; and a circuit including said relay and a connected telephone line whereby said relay is energized only when said trunk is connected with a calling telephone line, substantially as described. 75

6. In a connective system, lines; trunks; automatic means for connecting a trunk with a calling line; automatic secondary means for connecting a trunk with an operator's set; a relay associated with the trunk for rendering said automatic secondary means operative; and a circuit including said relay and a connected telephone line whereby said relay is energized only when said trunk is connected with a calling telephone line, substantially as described. 80

7. In a connective exchange system, a plurality of line circuits, a plurality of link circuits for interconnecting the same, a double set of automatic switches associated with said links, one set adapted to effect initial connection between links and lines, and the other set to be driven in a pre-determined manner to the wanted lines, mechanism adapted to be controlled by an operator for directing the second set of switches, and switches associated with the links adapted to be automatically driven to connect operator's mechanism with the link circuit associated with the calling line, and thereby to connect the operator's mechanism also with the switches of the second set, whereby the operator may select the wanted line, substantially as described. 85

8. In a connective system, an automatic primary selector switch; an automatic secondary selector switch; a line appearing in waiting contacts of said primary selector switch; a trunk appearing in wipers of said primary selector switch and in waiting contacts of said secondary selector switch; a source of current; a relay associated with said line and adapted to connect one terminal of said source of current to the test terminal of said line in said primary selector switch; and a relay associated with 90

5 said trunk and adapted to connect one side of said source current to the test terminal of said trunk in said secondary selector switch, said relay associated with said trunk being energized when said trunk is connected through said primary selector switch with a calling line, substantially as described.

9. In a connective system, lines; an 10 automatic primary selector switch; a trunk; means for connecting said trunk through said automatic primary selector switch to a calling one of said lines; an automatic secondary selector switch, having waiting contacts connected with said trunk; a source 15 of current; and a relay associated with said trunk and operated upon connection of said trunk with a calling line, adapted to complete a path from a waiting contact in said 20 secondary selector switch to one terminal of said source of current; and means whereby the wipers of said secondary selector switch may be stopped in connection with the trunk when said relay is operated, substantially as described.

10. In a connective exchange system, a plurality of subscribers' lines, primary selector switches associated with the lines, a plurality of connective link circuits having 30 fixed terminals in said switches, an operator's equipment including a telephone, and an automatic switch associated individually therewith containing terminals of branches from the link circuits, whereby the operator's outfit may be associated with any link for purposes of connection.

11. In a connective exchange system, a plurality of line circuits, a plurality of link circuits for interconnecting the same, a 40 double set of automatic switching means associated with said links, one set adapted to effect initial connection between links and lines and the other set to effect connection with wanted lines, a mechanism adapted to be controlled by an operator for directing the second set of automatic switching means, secondary switching means individual to each operator's set, and means associated with each link operative upon 50 initial connection of the same with a calling line to cause idle secondary switching means to connect its operator's mechanism with the link.

12. In a connective exchange system, a 55 plurality of line circuits, a plurality of connecting trunks, automatic switching means for connecting the same to calling lines, other automatic switching means for connecting the same to wanted lines, means for actuating said last mentioned automatic switching means comprising operator's number selecting circuit closers and differently characterized control circuits associated therewith, together with secondary switching means individual to the operator's sets

for selecting busy trunks and connecting their respective operator's sets and associated control circuits therewith.

13. In a connective exchange system, a plurality of line circuits; a plurality of connecting trunks; automatic means for connecting said trunks to calling lines; automatic means for connecting said trunks to wanted lines; operator's controlling means for controlling said second means; and automatic means individual to the operator's controlling means for associating said trunks individually with said operator's controlling means, substantially as described.

14. In a connective exchange system, a 80 plurality of line circuits; a plurality of trunks; automatic switching device individual to the lines for connecting said trunks to calling lines; automatic selective switching devices for connecting said trunks to 85 wanted lines; operator's controlling means for actuating said selective switching devices; and automatic means for associating said trunks individually with said operator's controlling means, substantially as described. 90

15. In a connective exchange system, a plurality of line circuits; a plurality of connecting trunks; automatic switches individual to the lines for connecting the trunks to calling lines; other automatic switches for 95 connecting the same to wanted lines; means controlled by an operator for actuating said second automatic switches; and automatic switches individual to the operator controlled means for connecting said operator-controlled means to a trunk upon said trunk's being connected to a calling line, substantially as described.

16. In a high speed electric switch, fixed and movable contacts, together with operating means therefor comprising an electromagnet, an armature therefor having operating connection with the movable one of said contacts, a knife edge on which said armature is fulcrumed, said armature having its 105 range of movement in one direction limited by abutting surfaces removed from said knife edge, and a retracting spring connected with said armature at a point from which it draws said armature when retracted 110 against both the knife edge and the limiting abutting surfaces whereby the armature is retained in position upon the knife edge by the pressure of the retracting spring.

17. The combination of a plurality of connecting circuits, of switching mechanism associated with said connecting circuits, a plurality of operators' positions, a plurality of sending mechanisms associated with each of said positions, and means whereby any 120 sending mechanism associated with any one of said positions may be associated with any one of said connecting circuits.

18. The combination of a plurality of connecting circuits, of switching mechanism 130

- associated with said connecting circuits, a plurality of operators' positions, a sending mechanism associated with each of said positions, and means whereby any sending mechanism may be associated with any one of said connecting circuits.
19. The combination of a plurality of connecting circuits, of switching mechanism associated with said connecting circuits, a plurality of operators' positions, three or more sending mechanisms, associated with each of said positions, and means whereby any sending mechanism associated with any one of said positions may be associated with any one of said connecting circuits.
20. The combination of a plurality of connecting circuits, of switching mechanism associated with said connecting circuits, three or more sending mechanisms for controlling said switching mechanism, and means whereby any sending mechanism may be associated with any one of said connecting circuits.
21. A telephone exchange system comprising subscribers' lines, trunks co-operating with the terminals of said subscribers' lines, a plurality of operators' positions, a telephone set and selectively operable apparatus at each of said positions, automatic switches associated with said trunks, telephone sets and apparatus adapted to connect an idle operator's telephone set and selectively operable apparatus with a trunk requiring attention.
22. A telephone exchange system comprising subscribers' lines, connecting trunks, a plurality of operators' positions, a telephone set and controlling apparatus at each of said positions, automatic Y switches associated with said trunks; telephone sets and controlling apparatus, and means whereby said automatic switches become active by reason of the connection of one of said trunks to one of said lines to connect an idle operator's telephone set and controlling apparatus to said trunk.
23. A telephone exchange system comprising a calling and a called line, a plurality of operators' positions, a telephone set and a sender at each of said positions, means for automatically connecting any idle operator's telephone set to said calling line to enable the operator to converse with the calling subscriber, and means under the control of the sender associated with said last mentioned telephone set for connecting the calling line to a called line.
24. A telephone exchange system comprising subscribers' lines, a number of connecting trunks less than the number of lines, means for automatically connecting an idle one of said trunks to one of said lines when calling, a plurality of operators' positions, a telephone set and switch controlling apparatus at each of said positions, means for automatically connecting an idle operator's telephone set to the trunk in use to enable the operator to converse with the calling subscriber, means including the switch controlling apparatus associated with the last mentioned telephone set for connecting a wanted line to said trunk, and means operative thereupon for disconnecting said telephone set and controlling apparatus from said trunk.
25. A telephone exchange system comprising subscribers' lines, a switching link circuit and an associated automatic switch adapted to connect with a selected one of said lines, a plurality of operators' positions, a telephone set and switch controlling equipment at each of said positions, means for automatically connecting an idle operator's telephone set and switch controlling apparatus to said link circuit, and further means for automatically disconnecting the operator's telephone set and switch controlling apparatus from the link circuit after the switch of the link circuit has been controlled to complete the desired connection.
26. In a telephone exchange system, the combination with a number of operators' connecting circuits, of automatic line switching mechanism for each connecting circuit adapted to connect said circuit with the desired line, a controller for operating any one of said mechanisms, tens and units relays for associating said controller with any one of said connecting circuits to operate its individual switching mechanism, and means actuated when said controller is taken for use by one connecting circuit for automatically locking out the other circuits therefrom.
27. The combination with a plurality of connecting circuits, of switching mechanism associated therewith, a sending device, said circuits being all normally in operative relation to said sending device, tens and units relays for associating said sending device with any one of said connecting circuits, an electromagnet means operated when said sending device is taken for use by one circuit for removing the remaining circuits from operative relation to said sending device.
28. The combination with a plurality of connecting circuits, of switching mechanism associated therewith, a sending device, said circuits being all normally in operative relation to said sending device, tens and units relays for associating said sending device with any one of said connecting circuits, automatic means operated when said sending device is taken for use by one circuit for removing the remaining circuits from operative relation to said sending device, and means operated when said sending device has completed its work for restoring

said remaining circuits to operative relation to said sending device.

29. The combination with a plurality of connecting circuits, of switching mechanism therefor, a key-board, tens and units relays for connecting said connecting circuits and said key-board, electromagnetic means arranged to associate said key-board with any one of said connecting circuits, and automatic means for locking out the remaining connecting circuits from such key-board.

30. The combination with a plurality of connecting circuits each terminating at one end in a connecting switch and at the other 15 end in automatic switching apparatus, a sending device, tens and units relays for associating said sending device with any one of said connecting circuits at a point intermediate the ends thereof, and means for 20 locking out the other circuits from said sending device.

31. The combination with a plurality of connecting circuits each terminating at one end in a connecting switch and at the other 25 end in automatic switching apparatus, of a sending device, tens and units relays for associating said sending device with any one of said connecting circuits, electromagnetic means automatically operated incident 30 to the use of the connecting circuit for associating said sending device with any one of said connecting circuits taken for use at a point intermediate the ends thereof.

32. The combination with a plurality of 35 connecting circuits each terminating at one end in a connecting switch, of automatic selector apparatus associated with the other end of said connecting circuit, a key-board, tens and units relays for associating said 40 key-board with any one of said connecting circuits, said tens and units relays arranged to automatically associate said key-board to the first connecting circuit taken for use at a point intermediate its ends to operate the associated selector and switching 45 apparatus, and means actuated when the key-board is taken for use with one circuit for removing it from operative relation to other of said circuits.

50. 33. In a telephone exchange system, the combination with lines, of a plurality of connecting circuits at the central office, automatic switching apparatus associated with said connecting circuits, means for connecting a calling line with any one of said connecting circuits, a sending device at the central office for controlling said apparatus, tens and units relays arranged to associate said sending device with any one of said 55 connecting circuits, and automatic means arranged to isolate said sending device for use with any one of said connecting circuits when taken for use and to disconnect the same when the selector switching apparatus 60

has united said connecting circuit with a 65 wanted line.

34. The combination with a plurality of connecting circuits, of switching mechanism associated therewith, a sending device and operator's telephone set, said circuits all 70 being normally in operative relation to said sending device and operator's telephone set, and electromagnetic means operated when said sending device and operator's telephone set are taken for use by one circuit for removing the remaining circuits from operative relation to said sending device and operator's telephone set.

35. The combination with a plurality of connecting circuits, of switching mechanism 80 associated therewith, a sending device and operator's telephone set, said circuits being all normally in operative relation to said sending device and operator's telephone set, automatic means operated when said sending device and operator's telephone set are taken for use by one circuit for removing the remaining circuits from operative relation to said sending device and operator's telephone set, and means operated when said 85 sending device has completed its work for restoring said remaining circuits to operative relation to said sending device and operator's telephone set.

36. The combination with a plurality of 90 connecting circuits terminating at each end in automatic switching apparatus, of a sending device, electromagnetic means arranged to associate said sending device with the first one of said circuits taken for use at a point intermediate the ends thereof, and means for locking out other circuits from 95 said sending device.

37. The combination with a plurality of 100 connecting circuits terminating at each end in automatic switching apparatus, of a sending device, and electromagnetic means automatically operated incident to the use of the connecting circuit for associating said sending device with any one of said connecting 105 circuits taken for use at a point intermediate the ends thereof.

38. The combination with a plurality of connecting circuits each terminating at one end in a connecting switch, of automatic 110 selector apparatus associated with the other end of said connecting circuits, a key-board and operator's telephone set, electromagnetic means arranged to automatically associate said key-board and operator's telephone set with the first connecting circuit taken for use at a point intermediate its ends to operate the associated selector switching apparatus, means actuated when the key-board and operator's telephone set are taken for use with one circuit for removing them from 115 operative relation to the other circuits.

39. In a telephone exchange system, the

- combination with a plurality of connecting circuits at a central office thereof, of switching mechanism associated with said connecting circuits, a sending device and operator's 5 telephone set at said central office, electromagnetic means arranged to associate said sending device and operator's telephone set with any one of said circuits, and means for locking out the other circuits from said 10 sending device and operator's telephone set.
40. In a telephone exchange system, the combination with operator's connecting circuits each terminating at both ends in an automatic switch, one of said switches serving to select a calling line and the other to extend a connection to a called line, of automatic sending apparatus adapted to be set in operation to cause the second mentioned automatic switch to be operated to extend the connection to the called line, means for associating said sending apparatus with a connecting circuit, and means automatically actuated by the sending apparatus in completing its operation to disassociate said 25 sending apparatus from such connecting circuit.
41. The combination of a plurality of connecting circuits, of switching mechanism associated therewith, a series of sending 30 mechanisms and operators' telephone sets, and means whereby the first idle sending mechanism and operator's telephone set of the series may be automatically associated with any one of said circuits.
42. The combination with a number of connecting circuits of mechanical line switching mechanism for each circuit, a series of sending mechanisms and operators' telephone sets, and means whereby the first 35 idle sending mechanism and operator's telephone set may be automatically associated with any one of said circuits taken for use.
43. The combination with a number of connecting circuits of mechanical line switching mechanism for said circuits a number of sending devices and operators' telephone sets, said circuits being all normally in operative relation to one of said 40 sending devices and operators' telephone sets, and means operated when said sending mechanism is taken for use by one circuit for transferring the remaining circuits in 45 operative relation to an idle sending mechanism and operators' telephone set.
44. The combination with a number of connecting circuits of line switching mechanism for said circuits, a number of sending mechanisms and operators' telephone sets, and means whereby each of said circuits 50 when used automatically employs an idle sending mechanism and operator's telephone set.
45. The combination with a number of connecting circuits, of mechanical switching 55 mechanism for said circuits, a number of sending mechanisms and operators' telephone sets, said circuits being all normally in operative relation to one of said sending mechanisms and operators' telephone sets, automatic means operated when said sending mechanism and operator's telephone set is taken for use by one circuit for transferring the remaining circuits into operative relation to the idle sending mechanism and operator's telephone set, and means operated when said busy sending mechanism has completed its work for restoring said remaining circuits in operative relation to said sending mechanism and operator's telephone set.
46. The combination with a group of connecting circuits, of a plurality of senders and operators' telephone sets, automatic means controlled in the use of any one of said connecting circuits adapted to bring one of said senders and operator's telephone sets into operative relation to such connecting circuit, and automatic means controlled by the use of one sender for switching another sender and operator's telephone set into condition to serve any of the other connecting circuits while the first sender is in use.
47. The combination of a pair of connecting circuits, of mechanical switching mechanism for said connecting circuits, a pair of key-boards and operators' telephone sets, means for automatically associating an idle one of said key-boards and an operator's telephone set to either connecting circuit taken for use, said key-board when so taken 100 for use serving to operate the switching mechanism of the connecting circuit.
48. In a telephone line selecting system, a plurality of senders and operators' telephone sets, a switch adapted in its normal 105 position to render one sender apparatus and a telephone set effective and in another position to bring another sender apparatus and telephone set into service.
49. In a telephone exchange system, the combination with subscribers' lines, connecting circuits and switches for connecting the calling lines with connecting circuits, of selectors adapted to extend said connecting circuits to other lines, a plurality of selector controllers and operators' telephone sets, and automatic switching means for associating idle controllers and idle telephone sets 115 one after another with said connecting circuits when they are taken for use.
50. In combination with subscribers' telephone lines, an operator's telephone set and sender, switching mechanism for automatically connecting the operator's telephone set to a calling subscriber's line, automatic switching mechanism for inter-connecting the lines in accordance with the numbers given to the operator, and means whereby 120 125

the sender controls the automatic switching mechanism to complete the desired connection.

51. In combination with subscribers' telephone lines, an operator's telephone set and sender, automatic mechanism set in motion by taking the telephone at any subscriber's station to connect the operator's telephone set with the calling line, automatic selective switching mechanism for connecting the calling line with a designated called line, and means whereby the sender controls the automatic switching mechanism to complete the desired connection.
52. In combination with subscribers' telephone lines, a plurality of operators' telephone sets and associated senders, mechanism for automatically connecting any operator's telephone set with any calling line, automatic selective mechanism for completing connections from a calling to a designated called line, and means for bringing the sender associated with an operator's telephone set which has been thus selected into control of the selective switching mechanism associated with the same calling line to control the selecting mechanism to make connection with the desired called line.

53. In combination with subscribers' telephone lines, a plurality of operators' telephones and associated senders, means for automatically connecting any operator's telephone not in use with any calling line, selective switching mechanism for connecting any calling line so connected with an operator's telephone to a designated called line, and means whereby the sender associated with the telephone so appropriated for orders governs the switching mechanism to select the wanted line, whereby incoming telephone calls are automatically distributed amongst operators.

54. In combination with subscribers' telephone lines, an operator's telephone and sender, means for automatically connecting the operator's telephone with a calling line, automatic switching mechanism for connecting the calling line to a designated called line, means whereby the sender governs the said switching mechanism in its selection, and automatic means for disconnecting the telephone and sender upon the completion of the connection.

55. In combination with subscribers' telephone lines, a plurality of telephones and senders, means for automatically connecting any telephone with any calling line, automatic selective mechanism for completing connection between any calling and any called line, means whereby the sender associated with a calling telephone line governs the corresponding switching mechanism to select the designated calling line, and means for disconnecting the telephone and sender upon completion of the con-

nection, whereby operators' telephones are automatically connected and disconnected with calling lines to effect an equitable distribution of the calls amongst the operators.

56. In combination with subscribers' telephone lines, a plurality of operators' telephones and senders, automatic selective switching mechanism for interconnecting said lines, means for automatically connecting an operator's telephone with a calling line and the corresponding sender with the selective switching mechanism for connecting said line with a designated called line.

57. In combination with subscribers' telephone lines, selective switching mechanism for connecting a calling line with a called line, a plurality of operators' telephones and senders, means for automatically connecting any telephone with any calling line and the corresponding sender with the switching mechanism, and means whereby the sender controls the switching mechanism to complete the connection to the designated called line.

58. In combination with subscribers' telephone lines, and automatic switching mechanism for connecting any calling line with any called line, a plurality of operators' telephones and senders, and means operated by taking the telephone at any calling station for connecting an operator's telephone with the line so calling and for connecting the sender with the switching mechanism for completing connection to the wanted line as described.

59. In combination with subscribers' telephone lines, and automatic switching mechanism for completing connection from a calling to a called line, a plurality of operators' telephones and senders, means operated by taking the telephone at the calling station to connect an idle operator's telephone with the calling line, means whereby the sender corresponding to said telephone controls the switching apparatus to complete the connection, and means for preventing a second connection with the said telephone while in use in receiving a call.

60. In combination with subscribers' telephone lines, and automatic switching mechanism for connecting a calling with a called line, a plurality of operators' telephones and keyset senders, means operated by taking the telephone at any calling station for automatically connecting any of said telephones with the calling line and the corresponding keyset sender with the switching mechanism for connecting said line to the designated called line, and means automatically operating to prevent appropriation of a telephone and keyset by more than one call, whereby originating calls are equitably distributed amongst the operators.

61. In combination with subscribers' telephone lines, automatic switching mecha-

nism for connecting any calling with any called line, a plurality of operators' telephones and a plurality of senders associated with each telephone, means for automatically connecting a telephone with a calling line and one of the senders with a switching mechanism associated with the same line, means for disconnecting the telephone from the calling line independently of the sender and for connecting it with another calling line, whereby operators' telephones are connected with calling lines as required for ordering calls, and senders are connected with switching mechanisms as required for selection.

62. In combination with subscribers' telephone lines and automatic switching mechanism for connecting a calling with a called line, an operator's telephone and a plurality of senders associated therewith, means for connecting the telephone with any calling line and an associated sender with the corresponding switching mechanism, and means for disconnecting the telephone from the calling line in readiness to taking another call without disconnecting the sender from the switching mechanism.

63. In combination with subscribers' telephone lines and automatic switching mechanism for connecting any calling with any called line, a plurality of operators' telephones and a plurality of senders for each telephone, means for automatically connecting an operator's telephone with a calling line and one of the associated senders with the switching mechanism for completing connection from said line to a called line, independent means for disconnecting the telephone from the calling line and the sender from the switching mechanism, and means for preventing the taking of a telephone or a sender by more than one line at a time, whereby subscribers' orders are distributed to operators' telephones and senders are distributed amongst the switching mechanisms as and for the periods required.

64. In combination with subscribers' telephone lines, a plurality of switching links for connecting a calling with a called line, a plurality of operators' telephones, a plurality of senders associated with each telephone, means for connecting the telephones with the calling lines for periods required to receive orders, means for connecting the corresponding sender with switching mechanisms for the periods required to operate said mechanisms, said telephones and senders being independently disconnectable.

65. In combination with communication lines connectable with one another as calling and called lines, an automatic switching

mechanism for connecting a calling with a called line, order receiving devices and sending devices, means for automatically connecting an order receiving device with a calling line and an associated sender with the corresponding switching mechanism, and for independently disconnecting them, whereby order receiving devices are distributed amongst calling lines and sending devices are distributed amongst switching mechanisms as and for the period required.

66. In combination with a plurality of calling lines, automatic selective mechanisms, order receiving devices and associated senders for operating the selective mechanisms, and means for automatically connecting an order receiving device with the calling line and a sender with the selective mechanism.

67. The combination of a plurality of calling and called subscribers' lines, switching mechanism for extending any calling line to any called line, a plurality of telephone sets and senders, means for automatically connecting any calling line to any telephone set, and for connecting any sender to the switching mechanism for operating the same, the operation of said switching mechanism serving to extend the calling line connected to the telephone set to any called line.

68. The combination of a plurality of calling and called subscribers' lines, switching mechanism for extending any calling line to any called line, a plurality of telephone sets and senders, means for automatically connecting any calling line to any telephone set, and means whereby any sender governs the switching mechanism to extend a calling line to a called line.

69. The combination of a plurality of calling and called subscribers' lines, switching mechanism for uniting calling and called lines, a plurality of telephone sets and senders, means for automatically connecting any calling line to any telephone set, and means whereby any sender may control the switching mechanism to extend the calling line connected to the telephone set to the called line.

70. The combination of a plurality of calling and called subscribers' lines, switching mechanism for uniting said lines, a plurality of telephone sets and senders, means whereby any of said lines when used automatically employs an idle telephone set, and means whereby any sender may be employed by said switching mechanism for causing its operation to unite any of said lines.

In testimony whereof I affix my signature.

EDWARD E. CLEMENT.
